(57) **CLAIM**

The ornamental design for an electric nasal aspirator, as shown and described.

DESCRIPTION

FIG. 1 is a perspective view of an electric nasal aspirator showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a schematic view thereof in cooperation with a cover when in use; and,

FIG. 9 is another schematic view of FIG. 8, wherein the cover is removed from the electric nasal aspirator.

The broken lines shown in FIGS. 1-7 depict portions of the electric nasal aspirator that form no part of the claimed design. The broken lines showing a cover in FIGS. 8 and 9 depict environmental subject matter and form no part of the claimed design.
